UNITED STATES PATENT OFFICE.

JOHN G. ALLEN, OF PHILADELPHIA, PENNSYLVANIA, ASSIGNOR TO A. W. ALLEN'S SONS, OF PHILADELPHIA, PENNSYLVANIA, A PARTNERSHIP.

TENSION DEVICE.

Application filed June 23, 1924. Serial No. 721,800.

To all whom it may concern:

Be it known that I, JOHN G. ALLEN, a citizen of the United States, and a resident of Philadelphia, county of Philadelphia, 5 State of Pennsylvania, have invented certain new and useful Improvements in Tension Devices, of which the following is a specification.

The present invention relates to feeding 10 mechanism for thread or yarn, and more particularly to a means for maintaining a uniform tension upon the thread.

Some of the objects of the present invention are to provide an improved thread tension device; to provide a tension device for thread which can be accurately adjusted to proportion the tension in accordance with the strength of the thread or yarn passing through the device; to provide a tension device which maintains a uniform tension upon the thread and prevents the thread from working out of the device during the feeding operation; to provide a tension device having a range of tension adjustment corresponding to the range of the strength of threads ordinarily employed; to provide a thread tension device having a plurality of thread pressure means, one or more of which can be caused to operate upon a thread according to the tension desired; and to provide other improvements, as will herein-after appear.

In the accompanying drawings, Fig. 1 represents a perspective of one form of tension device embodying the present invention; Fig. 2 represents a longitudinal section of the same showing the thread engaging surfaces in partially closed position; Fig. 3 represents a transverse section of the 40 device.

Referring to the drawings, one form of the present invention consists of a base block 10 which is provided with apertured ears 11 by which it is secured to a suitable support in operative relation with respect to the machine with which it is used. This block 10 is provided with an open slot 12, having oppositely disposed beveled sides 13 in order to form an interlocking joint with an insert 14, which is preferably of porcelain or some like material which forms a substantially frictionless surface. It is this insert 14 which supports the thread as it traverses the tension device, and in the present instance it has a thread engaging sur-

face formed by a plurality of substantially V-shaped corrugations 15 which project a suitable distance above the top edge of the block 10. A thread discharge opening 16 is formed in the end corrugation of the insert 14 to direct the thread to the point of use. 60

In order to place a tension upon the thread which is located across one or more of the corrugations 15, there is a second insert 17 which is suitably mounted in a top or closure member 18, hinged or otherwise fastened as shown at 19 to the block 10 in such a position that in closed position the two blocks are superposed one upon the other. This insert 17 is likewise of porcelain or other material which will produce a minimum of friction to a thread passing across its surface and also has an operating face formed by a plurality of corrugations 20. These corrugations are arranged to interfit with the corrugations 15 of the insert 14 so that when the cover block 18 is closed upon the base block 10 the two corrugated faces will interfit and accurately seat one upon the other. 70 A suitable lug 21 is provided for opening and closing the cover block 18 and the two inserts 14 and 17 are fastened in position respectively by set screws 22 and 23. 80

For the purpose of providing a means for varying the tension upon the thread, the insert 14 is provided with a plurality of through guide openings 24, 25, 26, 27 and 28, which are respectively located in the valleys between abutting corrugations 15 of 90 the base 10 and all of which open through a common slot 30 in the block 10. In the operation of the device, the thread 31, which is to be placed under a predetermined tension, is inserted through one of the 95 through guide openings, for example 26, and then carried transversely of the corrugations to the discharge guide opening 16. When the thread is so located, the closure part 18 is lowered and seats of its own weight 100 upon the lower insert 14, and in taking this position five pairs of opposing surfaces engage the thread 31 and act as a drag or brake to its movement through the device. This applied tension is proportional with respect 105 to the strength of the thread which is being drawn through the tension device and is never great enough to break the thread but is enough to maintain a continuous uniform tension upon the moving thread for the 110

purpose intended. Where a minimum of tension is required upon the thread, it will be inserted through the guide opening 24 and brought over the end corrugation, and but 5 two meeting faces of the device will engage the thread and the drag will be proportionately lessened, and where a maximum tension is desired the thread is passed upwardly through the guide opening 28, and extends 10 lengthwise of the device, so that all of the pairs of friction faces will act upon it and create a maximum tension which is unvarying during the entire feeding of the thread. In addition to creating a uniform tension 15 upon the thread for any particular thread strength there is also a means whereby it is impossible for the thread to work out of the tension device during the feeding operation and in tension devices as heretofore devised this has been a very serious difficulty, as obviously where the thread is 20 partially released during the feeding operation

there is a defect in the following yarn or thread winding step.

Having thus described my invention, I claim:

1. In a tension device, a member having a thread engaging surface, and a second member cooperating therewith and having a plurality of thread openings whereby the tension on said thread can be varied in accordance with the opening selected. 20

2. In a tension device, a member having a corrugated thread engaging surface, and a second member cooperating therewith having an interfitting corrugated thread engaging surface provided with a plurality of thread openings whereby the tension on said thread can be varied in accordance with the opening selected. 35

Signed at Philadelphia, county of Philadelphia, State of Pennsylvania, this 20th day of June, 1924.

JOHN G. ALLEN.
